UNITED STATES PATENT OFFICE.

EUGÈNE VÉRAN, OF PARIS, FRANCE, ASSIGNOR TO GOLO SLIPPER CO., OF NEW YORK,
N. Y., A CORPORATION OF NEW YORK.

DESIGN FOR A FEATHER-TRIMMED SHOE.

Application filed May 21, 1927. Serial No. 22,116. Term of patent 7 years.

To all whom it may concern:

Be it known that I, EUGÈNE VÉRAN, a citizen of France, and a resident of Paris, France, have invented a new, original, and ornamental Design for Feather-Trimmed Shoe, of which the following is a specification, reference being had to the accompanying drawing, forming part thereof.

The drawing is a perspective view showing a feather trimmed shoe embodying the present invention.

I claim:

The ornamental design for a feather trimmed shoe substantially as shown.

EUGÈNE VÉRAN.
